DISPLAY SHELF

William E. Crawford, 5428 Spring Road,
Bladensburg, Md.

Filed Mar. 26, 1962, Ser. No. 69,434

Term of patent 14 years

(Cl. D33—3)

FIG. 1 is a front elevational view of a display shelf, showing my new design,

FIG. 2 is a top plan view thereof,

FIG. 3 is a side elevational view as it appears with the broken lines showing of the flowers omitted for convenience of illustration.

I claim:

The essential features of the design reside in the full line portions on the drawing. The back of the design is substantially plain and unornamented.

The ornamental design for a display shelf, as shown and described.
